SCRAPER FOR A VESSEL CLEANING MACHINE

Harry Cunliffe, Leasowe, Wirral, England

Application July 20, 1956, Serial No. 42,319

Term of patent 14 years

(Cl. D9—6)

Fig. 1 is a plan view of a scraper for a vessel cleaning machine embodying my new design;

Fig. 2 is a side view in the direction of the arrow II of Fig. 1;

Fig. 3 is an inverted plan view;

Figs. 4 and 5 are end views in the direction of arrows IV and V, respectively, of Fig. 3; and

Fig. 6 is a side view in the direction of arrow VI of Fig. 1.

I claim:

The ornamental design for a scraper for a vessel cleaning machine, substantially as shown.
